(57) CLAIM

The ornamental design for a candle wick cutter, as shown and described.

DESCRIPTION

FIG. 1 is a perspective view of a candle wick cutter, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective view showing the candle wick cutter of the present invention in operation.

The broken lines in FIG. 8 are for informational purposes only and form no part of the claimed design.

1 Claim, 5 Drawing Sheets

FIG. 1.

FIG. 2.

FIG. 3.

FIG. 4.

FIG. 5.

FIG. 6.

FIG. 7.

FIG. 8.
